UNITED STATES PATENT OFFICE

HARRY F. SMITH, OF DAYTON, OHIO, ASSIGNOR TO FRIGIDAIRE CORPORATION, OF DAYTON, OHIO, A CORPORATION OF DELAWARE

REFRIGERATING APPARATUS

Application filed March 28, 1929. Serial No. 350,711.

This invention relates to refrigerating apparatus and particularly to tubing used in such apparatus for heat exchange purposes.

One of the objects of the invention is to provide a plurality of fluid circuits or passages which are substantially identical thermally, but are separate and isolated hydraulically.

Another object is to provide an improved arrangement of fluid circuits or passages in intimate heat exchange relation with each other.

More specifically stated, it is an object of the invention to provide an improved tube which can be formed and used mechanically as a single tube, but which has a plurality of independent or hydraulically isolated circuits.

Another object is to provide a tube formed of a number of independent longitudinal sections or tubes which when assembled make a unitary circular tube, which can be worked and handled as an ordinary round tube.

Another object is to provide improved means for holding the sections together.

Still another object is to provide all of the passages of the tube with a large heat exchange surface presented to the environment of the whole tube.

Further objects and advantages of the present invention will be apparent from the following description, reference being had to the accompanying drawings, wherein a preferred form of the present invention is clearly shown.

In the drawings:

Fig. 1 is a side elevation of a section of tubing embodying the invention, and

Fig. 2 is a section on the line 2—2 of Fig. 1.

Referring to the drawings 10 designates generally a tube which is formed of any suitable number of longitudinal sections or tubes such as 11 and 12, made of thin metal of good thermal conductivity such as the drawn copper commonly used for heat exchange tubing in refrigerating apparatus. Each of the sections or tubes 11 and 12 is shaped in the form of a portion of a circle so that when the tubes are placed together they form a complete circle. For example the tubes 11 and 12 shown

in Fig. 2 are sectors of a circle each being substantially a semi-circle. The flat sides 13 and 14 of the sector tubes are placed together and the tubes are fastened together by a member or members 15 which surround the complete tube 10. This member or members preferably constitute heat exchange fins or finning and may be formed of independent fins placed about the tubes, or as shown in the drawings, it may be a thin copper strip wound edgewise to form a helix. The parts described may be assembled and held together in any desired manner, for example the tubes 11 and 12 may be laid together, the fin 15 wound about the assembly and the whole dipped in molten solder. This forms a strong mechanical bond between the sections or independent tubes and the fins, and provides a good thermal contact between the several tubes, and extensive heat exchange surface between each separate tube and its environment or atmosphere in which the tubing may be used.

This arrangement provides what is to all outward appearances a single circular tube which may be formed, handled and used in exactly the same manner and in the same places in which ordinary round tubing is used. However, the construction of this tube by using a plurality of independent smaller tubes provides a number of separate passages or circuits for the circulation of any desired fluids. Obviously the circuits or passages are hydraulically isolated but are in intimate thermal relation with each other so as to be substantially identical thermally.

While the form of embodiment of the invention as herein disclosed, constitutes a preferred form, it is to be understood that other forms might be adopted, all coming within the scope of the claims which follow.

What is claimed is as follows:

1. A tube consisting of separately formed longitudinal sections providing separate and distinct passages for the tube, and means for holding the sections together to complete the tube and to provide extended radiating surfaces on the exterior thereof.

2. A tube consisting of separately formed longitudinal sections providing separate and

distinct passages for the tube and fins about the sections to hold them together to complete the tube and to provide extended radiating surfaces therefor.

5 3. A tube consisting of separately formed longitudinal sections providing separate and distinct passages for the tube and a fin spirally wound about the sections to hold them together to complete the tube and provide extended radiating surfaces therefor.

10 4. A circular tube consisting of separately formed longitudinal sections, each constituting a portion of the circle of the tube and providing a separate and distinct passage therefor, and fins about the sections to hold them together to complete the tube and to provide extended radiating surfaces therefor.

15 5. A circular tube consisting of separately formed longitudinal sections, each constituting a portion of the circle of the tube and providing a separate and distinct passage therefor, and a spiral fin wound about the assembled sections for holding them together and to provide extended radiating surfaces therefor.

20 6. A circular tube consisting of two separately formed half round sections to provide separate and distinct passages for the tube, said sections being applied with their flat surfaces in contact to complete the circle of the tube, and fin means about the tube for holding its sections together and to provide extended radiating surfaces therefor.

25 7. A circular tube comprising a multiplicity of longitudinally extending segmental sections independently formed to provide separate and distinct passages for the tube, said sections being applied with their flat surfaces in contact to complete the circle of the tube, and a spiral fin wound about the outside of the tube for holding the sections together and to provide extended radiating surfaces therefor.

30 In testimony whereof I hereto affix my
signature.

HARRY F. SMITH.
